UNITED STATES PATENT OFFICE.

DANIEL W. TOWER, OF GRAND RAPIDS, MICHIGAN.

FURNITURE-FASTENING DEVICE.

No. 843,717.

Specification of Letters Patent.

Patented Feb. 12, 1907.

Application filed February 12, 1906. Serial No. 300,636.

To all whom it may concern:

Be it known that I, DANIEL W. TOWER, a citizen of the United States, residing at Grand Rapids, in the county of Kent, State 5 of Michigan, have invented certain new and useful Improvements in Furniture-Fastening Devices, of which the following is a specification.

This invention relates to improvements in 10 fastening devices for furniture or "joint bolts," as they are sometimes called.

This invention is especially designed and intended for use to retain the superstructure, as a mirror-standard, on the main base or 15 body of a dressing-table or to retain the parts of knockdown furniture securely together.

This invention has to do with improvements in such devices whereby the assembling of the parts is greatly facilitated and 20 whereby the bolt in use does not have separable parts likely to become lost and to provide an improved and convenient construction for inserting the fastener in place in the furniture.

25 Further objects will appear from the detailed description to follow.

I accomplish the objects of my invention by the devices and means described in the following specification.

30 The invention is clearly defined, and pointed out in the claims.

A structure embodying the features of my invention is clearly illustrated in the accompanying drawings, forming a part of this 35 specification, in which—

Figure 1 is a detail rear elevation view of my improved structure as applied to the manufacture of furniture to secure the superstructure, as a mirror-stand, on the base 40 or body portion of a dresser or table below. Fig. 2 is an inverted detail plan view of the structure appearing in Fig. 1. Fig. 3 is a detail sectional view taken on line 3 3 of Fig. 2. Fig. 4 illustrates a wrench or crank for inserting the bolt into the wood.

45 In the drawings, similar letters of reference refer to similar parts throughout the several views.

Referring to the lettered parts of the 50 drawings, on the top board A of a dresser is the mirror-standard A', which is secured thereto by my improved device. A semi-circular recess a is cut in the under side of the top board A with parallel sides out to the 55 edge thereof, and a slot a' is cut into the back thereof to substantially the center of the re-

cess. A bolt B is provided with a wood-screw thread for insertion up into the under side of the mirror-frame A' or other superstructure. The lower end of this bolt is provided with a 60 screw-thread, on which is placed a nut B', which can be screwed up and down thereon. Suitable notches are formed in the nut, so that it can be readily turned by inserting any instrument, such as the end of a screw-driver 65 or the wrench C, into the notches and using the same like a lever to turn the nut. The opposite sides of the bolt B between these screw-threads are flattened, as at b b, either by making an indentation therein or by cutting away the sides of the screws. This part 70 can be squared or made irregular in form by any suitable means. The wrench C, with a series of slots c, is provided for grasping the bolt at this point, the wrench being adapted 75 to varying sizes. This wrench is preferably provided with a crank-handle D, so that the screws can be turned in or out very readily.

In use the bolt B is screwed into the wood 80 by means of the wrench C, so that the nut B' will reach such a point as to substantially clamp the intervening portion of the top A. The nut can then be turned back a little, so as to permit the bolt to be readily slipped 85 into the slot a' and then by using a screwdriver or by inserting the end of the wrench C flatwise the nut B can be screwed down securely on the intervening part of the top and support the mirror-standard or other 90 superstructure very effectively in position.

Attention is called to the fact that by 95 simply loosening the nut B' without removing it the top A' can be removed by passing the body of the bolt B outwardly through the open slot a'. This is of great advantage 100 both in the matter of assembling the furniture in the first place and also in disassembling it as for the purpose of shipment. It results in a great saving and avoids the possible injury to the parts and to the joint-bolt 105 or loss of any parts, the parts being always in proper position for immediate use with the smallest possible amount of adjustment.

Having thus described my invention, what I claim as new, and desire to secure by Letters Patent, is—

1. In a furniture-fastening, the combination of a top board A, having the recess a and an open slot a' therein; a superstructure A'; a bolt B flattened at b provided with a wood-screw thread for insertion into the superstructure; and a notched and threaded nut 110

B' on the lower end of the bolt, arranged to clamp the top board at each side of the open slot a', as specified.

2. In a fastening device, the combination of two parts to be joined, one of which contains a recess with an open slot through to the central part thereof; a bolt for joining the parts together, provided at one end with a wood-screw thread and provided with a threaded nut on the opposite end, the wood-screw being inserted into the one member

and the nut being arranged in the recess in the opposite member, in position to clamp at the opposite sides of said slot, coacting for the purpose specified.

In witness whereof I have hereunto set my hand and seal in presence of two witnesses.

DANIEL W. TOWER. [L. S.]
